UNITED STATES PATENT OFFICE.

ROBERT S. MIX, OF ATLANTA, NEW YORK.

NECK-YOKE ATTACHMENT.

1,146,643.

Specification of Letters Patent. Patented July 13, 1915.

Application filed December 13, 1913. Serial No. 806,512.

To all whom it may concern:

Be it known that I, ROBERT S. MIX, a citizen of the United States, residing at Atlanta, in the county of Steuben and State 5 of New York, have invented certain new and useful Improvements in Neck-Yoke Attachments; and I do hereby declare the following to be a full, clear, and exact description of the invention, such as will enable others 10 skilled in the art to which it appertains to make and use the same.

My invention relates to attachments for neck yokes whereby the draft pole of a vehicle may be supported in a reliable manner.

15 An important object of my invention is to provide an attachment for neck yokes consisting of a novel form of supporting means for the draft pole of a vehicle which is constructed to withstand rough usage and is 20 not liable to become broken.

Another important object of my invention is to provide a device of the character described which consists of a leather ring which is secured to the neck yoke and is 25 reinforced by novel means whereby the life of the device is materially increased and accidents due to breaking of the connection between the yoke and draft pole and causing the horses to run away is eliminated.

30 The invention further aims to improve pole supporting means of the character described so as to render them more practical, reliable and efficient, cheap to manufacture and more commercially desirable.

35 The above and additional objects are accomplished by such means as are illustrated in the accompanying drawings, described in the following specification and then more particularly pointed out in the claim which 40 is appended hereto and forms a part of this application.

With reference to the drawings, wherein I have illustrated the preferred embodiment of my invention as it is reduced to practice, 45 and throughout the several views of which similar reference numerals designate corresponding parts, Figure 1 is a front elevation of my device showing it attached to a neck yoke, and Fig. 2 is a vertical sectional view 50 taken on line 2—2 of Fig. 1 illustrating the device as it would appear in assembled position relative to the neck yoke.

Referring to the drawings forming a part of this specification and in which like numerals are employed to designate corresponding parts, the numeral 3 designates a

metallic band which is adapted to surround the neck yoke 4. The free ends 5 of the band 3 are clamped in engagement with a leather ring 6 and held in that position by 60 bolts 7 or other suitable fastening means. The leather ring 6 is composed of a plurality of layers of leather that are stitched adjacent their edges as at 8. The inner end of the ring 6 is provided with a straight edge 65 while the outer end is rounded and slightly enlarged.

As a means for strengthening the ring 6 there have been provided flat metallic rings 8 and 9 that are adapted to be secured to 70 the ring 6 upon opposite sides thereof adjacent its inner edge, by bolts 10 or other suitable fastening means that are inserted through the rings and leather ring 6. These rings 8 and 9 are curved in cross section and 75 when tightly secured by means of the bolts 10 produce a slight curve in cross section to the leather ring 6 which facilitates a great gripping engagement of the ring 6 with a draft pole not shown. 80

Inserted through the band 3 and neck yoke 4 centrally of the side edges of the band is an elongated bolt 11. This bolt 11 is disposed angularly with relation to the vertical axis of the neck yoke 4 and has threaded 85 upon its upper terminal which is extended beyond the edge of the band 3, a suitable nut 12. The lower end of the bolt 11 is offset and provided with an eye 13 that is disposed in engagement with one of the free 90 terminals 5 of the band 3 at a point between the fastening means 7. A rolled ear 14 is formed adjacent the outer edge of the flat ring 9 and is adapted to receive a connecting ring or link 15 that is inserted through the 95 eye 13 on the bolt 11 and serves to connect the bolt 11 with the ring 9.

It will be seen that when the draft pole of a vehicle running gear, not shown, is inserted through the leather ring 6, the greater 100 portion of the strain is placed upon the bolt 11 thus increasing the rigidity and life of the device. The angular disposition of the bolt 11 and offset portion in combination with the curvature of the ring 6 facilitates 105 the engagement of the device with the draft pole in a reliable and efficient manner and eliminates all rattling or unnecessary wear upon the parts of the device.

It is desirous of emphasizing the fact that 110 the strain on the device is taken up by the arrangement of the bolt 11 and connected

parts in such a way that wearing, or breaking of the leather ring 6 is positively eliminated thus preventing accidents and possible injury to occupants of the vehicle.

5 In reduction to practice, I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various minor changes in details of construction, proportion and arrangement of parts may 10 be resorted to, when required, without sacrificing any of the advantages of my invention, as defined in the appended claim.

What is claimed is:—

15 The combination with a neck yoke and a depending flexible pole supporting member secured thereto, of a bolt inserted through

the neck yoke and being disposed in a downwardly and forwardly inclined plane relative thereto, an eye formed on the lower end of said bolt, the other end of said bolt 20 being screw threaded, a nut turned on the screw threaded end of said bolt and engaging said neck yoke, a metallic ring secured to said pole supporting member, an eye carried by said ring and a link pivotally 25 connected with the eye on the bolt and the eye on the ring, said eye on the bolt being disposed in engagement with the upper part of the pole supporting member on the front face thereof. 30

35 In testimony whereof I affix my signature in presence of two witnesses.

ROBERT S. MIX.
